UNITED STATES PATENT OFFICE.

REINHOLD HAKEWESSELL AND FRED K. RAND, OF HARTFORD,
CONNECTICUT.

BEVEL-PROTRACTOR.

SPECIFICATION forming part of Letters Patent No. 424,977, dated April 8, 1890.

Application filed January 24, 1889. Serial No. 297,379. (No model.)

To all whom it may concern:

Be it known that we, REINHOLD HAKEWESSELL and FRED K. RAND, of Hartford, in the county of Hartford and State of Connecticut, have invented certain new and useful Improvements in Bevel-Protractors, of which the following is a full, clear, and exact description, whereby any one skilled in the art can make and use the same.

10 The object of our invention is to provide a bevel-protractor that shall be capable of a more extended use and of wider application than the protractors of the prior art.

To this end our invention consists in the 15 combination of a sliding bar, an index-arm connected to said bar, and a triangular part to which said arm and bar are pivoted.

It further consists in the combination of the triangular part having working-edges, the 20 index-arm pivoted to said part, the clamp adjacent to the pivot, and the sliding bar; and it further consists in details of the several parts and in their combination, as more particularly hereinafter described, and pointed 25 out in the claims.

Referring to the drawings, Figure 1 is a plan view of one form of our improved device, showing the index set at zero of the graduated arc. Fig. 2 is a detail plan view 30 of the same, showing the index set at forty-five degrees and the edges of the bar and one edge of the triangle parallel to each other. Fig. 3 is a detail view in crosswise section on plane α α of Fig. 2. Fig. 4 is a detail view of the device, illustrating one of its uses in connection with a flanged part.

In the accompanying drawings, the letter a denotes a triangular part, that is preferably made of steel, and has for a certain extent 40 along each edge a straight part. Near the apex of one of the angles of this triangular part, as at b , an index-arm c is pivoted on a stud d , that has an enlarged head fitting a recessed socket on the under side of the triangular part, and a stem that extends upward through an opening in the triangular part smaller than the head of the pivot and passing through the index-arm. This stem is threaded to receive a nut e , which forms the 45 immediate means of clamping the arm in position by turning the nut down upon the arm.

The outer end of the arm is undercut, so that a space is left underneath it to receive the edge of a sliding bar or rule f . This bar has a lengthwise groove f' , into which the flanged portion on the outer end of the arm projects in such manner as to prevent the bar from having anything but a sliding movement on the arm and triangular part. A particular advantage of this construction is due to the 55 fact that two working-edges—one a' on the triangular part and another f'' that is the outer edge of the bar or rule—can be set parallel to each other or at any degree of angular divergence, thus enabling the tool to be 60 thrust in between a face-plate and the back surface of a piece of work, or held with one of the edges against a fixed part of a machine-tool and the other against the work or a tool to measure the angular divergence between 65 two surfaces or to set them at a desired degree. A further advantage follows from the peculiar construction of the triangular part with short straight surfaces near the adjacent 70 angles of the edge a' , that enable the tool to 75 be used, as illustrated in Fig. 4, to reach past a projecting flange to determine the angle between an inner surface and the outer edge or periphery of the flanged part.

By the term "triangular part" we do not 80 mean to limit the construction of that part marked a to the peculiar form shown in the drawings, as the main advantages of our improvement will be present if the rule or bar is so connected to this triangular part as to 85 provide the two working-edges facing outward and the two other edges of the triangular part adjacent to the rule and located on the opposite side of the index-arm.

The form of pivot and clamping device 90 shown is preferred on account of the simplicity of construction; but we do not limit ourselves to this particular form.

We claim as our invention—

1. In combination with a triangular part 95 pivotally attached to a sliding bar at one apex and having the working-edges and graduated scale, a sliding bar removably clamped thereto, the index-arm pivoted to the triangular part and attached to the said sliding bar, 100 and the clamp for securing the parts temporarily, all substantially as described.

2. In combination with the triangular part having the squared ends and bearing a graduated scale, a sliding bar connected to an index-arm, the index-arm pivoted to the triangular part near the apex of one of the angles, and the clamp device for controlling the movement of the index-arm and the bar, all substantially as described.
3. The herein-described device, consisting of a triangular-shaped piece with working edges, the sliding bar attached to said part near one apex and to the index-arm and with its outer edge overhanging said apex, the index-bar pivoted to the triangular part, and the clamping device that controls the move- ments of the index-arm and the bar, all substantially as described.
4. In combination with the triangular part having the squared ends, the grooved sliding bar or rule connected to the index-arm, the index-arm pivoted to the triangular part and having a flange overhanging and engaging the groove in the sliding bar, and the clamp device, all substantially as described.

REINHOLD HAKEWESSELL.
FRED K. RAND.
